(57) **CLAIM**

The ornamental design for a skirting board for refrigerator as shown and described.

DESCRIPTION

FIG. 1 is a front elevation view of a first embodiment of a skirting board for refrigerator according to our new design; FIG. 2 is a rear side elevation view of the first embodiment of the skirting board for refrigerator; FIG. 3 is an enlarged left side elevation view of the first embodiment of the skirting board for refrigerator; FIG. 4 is an enlarged right side elevation view of the first embodiment of the skirting board for refrigerator; FIG. 5 is a top plan view of the first embodiment of the skirting board for refrigerator; FIG. 6 is a bottom plan view of the first embodiment of the skirting board for refrigerator; FIG. 7 is a perspective view of the first embodiment of the skirting board for refrigerator; FIG. 8 is a perspective view of the first embodiment of the skirting board for refrigerator, shown in an environment of use; FIG. 9 is a front elevation view of a second embodiment of the skirting board for refrigerator; FIG. 10 is a rear elevation view of the second embodiment of the skirting board for refrigerator; FIG. 11 is an enlarged left side elevation view of the second embodiment of the skirting board for refrigerator; FIG. 12 is an enlarged right side elevation view of the second embodiment of the skirting board for refrigerator; FIG. 13 is a top plan view of the second embodiment of the skirting board for refrigerator; FIG. 14 is a bottom plan view of the second embodiment of the skirting board for refrigerator; FIG. 15 is a perspective view of the second embodiment of the skirting board for refrigerator; and, FIG. 16 is an enlarged cross-sectional view of the second embodiment of the skirting board for refrigerator along lines 16-16 shown in FIG. 9.

(Continued)

The evenly spaced broken lines in the drawings depict portions of the skirting board for refrigerator that form no part of the claimed design.

The dot-dash broken lines in the drawings depict environmental subject matter only that forms no part of the claimed design.
